UNITED STATES PATENT OFFICE.

FRANK H. ROBERTS AND ALBERT C. LUYCKX, OF DETROIT, MICHIGAN;
SAID ROBERTS ASSIGNOR TO SAID ALBERT C. LUYCKX AND WILLIAM
J. LUYCKX, OF SAME PLACE.

INK-WELL FOR SCHOOL-DESKS.

SPECIFICATION forming part of Letters Patent No. 372,398, dated November 1, 1887.

Application filed March 12, 1887. Serial No. 230,687. (No model.)

To all whom it may concern:

Be it known that we, FRANK H. ROBERTS and ALBERT C. LUYCKX, citizens of the United States, residing at Detroit, in the county of Wayne and State of Michigan, have invented certain new and useful Improvements in Ink-Wells for School-Desks; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to certain improvements in ink-wells, being designed especially for school-desks.

The object of our invention is to construct a simple and cheap device that may be attached to the end or ends of the desk-top, and to the under face of the same outside of the legs or supports, and in such a manner that the well may be readily attached and detached, and to allow the well to be projected from under the desk-top when using, and to swing under said top when not in use, the well being so constructed that when turned under the desk-top the mouth of the well will be closed to prevent evaporation of the ink; and our invention consists in the construction of parts, as hereinafter specified, and pointed out particularly in the claims.

In the accompanying drawings, forming a part of the specification, Figure 1 is an end perspective of a school-desk containing our invention. Fig. 2 is an enlarged top plan showing connecting parts, the movements of which are indicated by dotted lines. Fig. 3 is an enlarged perspective of the ink bottle or well. Fig. 4 is an enlarged section through desk-top and joining parts, the well being in the position shown in Fig. 1, the section taken on dotted line $x-x$ of Fig. 2. Fig. 5 is an enlarged perspective of the two parts sliding gate or key. F in the drawings represents the common standard to a school-desk, and D the desk or top, which is also common. On the under face of the top D, leading from the end Z', we form a channel, S, having an undercut along its edges,

forming the sloping sides o o. In Fig. 5 we show a two-part key, Z Z, having sloping edges d d. The slant of the edges of the key coincides with the slant o of the channel formed in the top D. The united width of the parts of the key is equal to the width of the channel S, whereby said key fills snugly said channel when inserted, as shown in Figs. 1, 2, and 3. We form in the joining edges of the parts of the key a semicircular opening having a slanting edge, t, so that when the parts Z Z of the key are joined a flaring hole is formed through the key.

In Fig. 3 we show the ink-well, which we make, preferably, of glass. Said well is provided with the circular mouth m for filling and for the insertion of the pen. C is the chamber. n is the neck, which we make solid, and is of the form of an inverted cone having the inclined annular side a, with annular flanges a'. The incline of the neck n corresponds with the incline t of the gate, and the neck n is made sufficiently large to fill the opening formed in the two-part gate Z Z. When said parts of the gate are placed around the neck, as shown in Figs. 2 and 4, the length of the neck n and the thickness of the gate are the same. By this construction, when the gate Z Z is forced into the channel S, the neck n will slide with said gate into it, as shown in Fig. 4, whereby the well becomes suspended under the desk-top, and may be turned about on the neck n, journaled in the gate, and to remove the well from the desk-top you simply withdraw the gate.

Around the mouth m of the well we form an annular recess, e, or depression, (see Fig. 3,) and filling said annular recess is a rubber ring, R, which is held in position by the annular recess. The upper edge of the ring R comes slightly above the end of mouth m of the well. It will be observed that by this arrangement when the well W is swung around, as shown in Figs. 1 and 4, the rubber ring R is forced against the under face of the desk-top, thus closing the mouth of the well, preventing the ink from evaporating when the well is not in use. It will be observed, also, that the well W is U-shaped, and as it is journaled in the sliding gate to project the well, so as to insert the

pen, the operator gives the well (when in the positions of Figs. 1 and 4) a quarter-turn, when the mouth *m* of the well will be swung out from under the desk-top to the position shown 5 in Fig. 2.

The manner of attaching the well to the desk-top allows it to be turned either to the right or left, as shown by the arrows in Fig. 2, and should anything come in contact with the well 10 when projected, as shown in Fig. 2, it would swing around under the desk-top out of the way without injuring the well; and to remove the well the drawing outward on the gate to the dotted position in Fig. 2 will detach the 15 well from the desk-top, as hereinbefore stated, when the well can be cleaned out or emptied of its ink.

We have shown a rubber ring around the mouth of the well, so as to close the mouth 20 when swung under the desk-top and to make it air-tight. The same result may be accomplished by placing a strip of rubber on the under face of the desk-top over the swinging point of the mouth, as shown at 3 to the right 25 of Fig. 4, and swinging the mouth of the well under it; or any flexible material—such as leather or felting—may be so employed, where-

by we are able to dispense with the rubber ring *R*. Therefore we desire our invention to cover such changes. 30

Having thus fully set forth our invention, what we claim as new, and desire to secure by Letters Patent, is—

1. In combination with the desk-top and its standard, the chamber formed in the under face of the top, the two part key having the central opening, the ink-well journaled in said two-part key and having the conical lug, and the annular recess formed around the mouth of the well, with rubber or flexible ring located in 40 said chamber, as and for the purposes set forth.

2. In combination with the desk-top, the **U**-shaped ink-well having the neck *n*, said neck being journaled in the under face of the desk-top, whereby the mouth *m* of the well may be 45 swung under the top or projected therefrom, as and for the purposes specified.

In testimony whereof we affix our signatures in presence of two witnesses.

FRANK H. ROBERTS.
ALBERT C. LUYCKX.
